UNITED STATES PATENT OFFICE.

CHARLES A. WAY, OF CHARLESTOWN, NEW HAMPSHIRE.

DESIGN FOR A PUZZLE-CARD.

SPECIFICATION forming part of Design No. 26,529, dated January 12, 1897.

Application filed November 7, 1896. Serial No. 611,411. Term of patent 7 years.

To all whom it may concern.

Be it known that I, CHARLES A. WAY, a citizen of the United States, residing at North Charlestown, in the county of Sullivan, State of New Hampshire, have invented and produced a new and original Design for Puzzle-Cards, of which the following is a specification, reference being made to the accompanying drawing, showing a part thereof.

- 10 The drawing shows in plan view a puzzle-card showing my design.

The leading feature of my design for a puzzle-card consists in a card having three holes of different shapes, there being one square hole *a*, one circular hole *b*, and one triangular hole *c*. These three unlike holes *a b c* may

be arranged one above the other or otherwise, as desired. The altitude of the triangular hole *c* and the diameter of the circular hole *b* and the side of the square hole *a* are all of 20 equal measurements.

I claim—

The design for a puzzle-card herein shown and described.

In testimony whereof I have signed my 25 name to this specification in the presence of two subscribing witnesses.

CHAS. A. WAY.
